UNITED STATES PATENT OFFICE.

JACOB A. JACKSON, OF DES MOINES, IOWA.

CHECK OR ACCOUNT BOOK.

SPECIFICATION forming part of Letters Patent No. 290,432, dated December 18, 1883.

Application filed November 20, 1882. (No model.)

To all whom it may concern:

Be it known that I, JACOB A. JACKSON, of Des Moines, in the county of Polk and State of Iowa, have invented an Improved Check or 5 Account Book, of which the following is a specification.

My invention relates to stubless check-books; and it consists in combining a series of graduated balance-sheets with the edge of a 10 cover that has a tablet-surface inside and is adapted to retain a collection of detachable blanks.

Heretofore stubless checks have been bound between covers and a series of record-leaves 15 or fly-sheets of uniform size combined therewith in various ways. The inside surface of a cover has also been ruled and prepared to be used as a balance-sheet and continuous record of successive transactions; but combining 20 a series of balance-sheets that are graduated in length with a cover having a tablet-surface in such a manner that the totals of successive entries footed up on each sheet will be contiguous and visible at the same time when 25 the book is open and the tablet accessible for use, as frequently required in giving checks and keeping accounts, is novel and greatly advantageous.

Figure 1 of my accompanying drawings is a 30 top view of my improved book opened and spread out flat. Fig. 2 is a perspective view. Together these figures clearly illustrate the construction, operation, and utility of my complete invention.

35 *a* and *b* represent the two covers or two connected sides of the cover. They are preferably made of paper-board, and may vary in size and shape as desired.

c represents a blank space, tablet, or slate 40 surface, formed on or attached to the inside of

the cover-section *a* by means of paste or in any suitable way in such a manner that words and figures may be written thereon and erased at pleasure.

Nos. 1 2 3 represent a series of balance-sheets, differing in length, as shown, fixed to the inside and outer edge of the cover-section *a* by means of a series of wire fastening devices, 4 5 6, or in any suitable way, so as to allow the sheets to be turned up or lifted from the tablet *c* or to be lifted from each other, as required, to become accessible to write thereon and to read their contents successively, or detachably fastened, to be removed and filed away and replaced by corresponding sheets 55 whenever desired.

d represents a series of checks or blanks bound between the two cover-sections *a* and *b* by stitching, with metal fastening devices, or in any suitable way in such a manner that they can 60 be successively detached by means of a line of perforations, *f*, in each blank, running parallel with its bound edge; or the cover-sections may be connected by means of a flexible strip or back and the checks or blanks *d* formed in 65 blocks and simply placed within the complete cover without fastening, or fastened flat upon the section *b* only in such a manner that the perforated lines *f* may be dispensed with.

I claim as my invention—

An improved check or account book, composed of a cover, *a* *b*, having a tablet-surface, *c*, a series of graduated balance-sheets, 1 2 3, and a collection of checks or blanks, *d*, substantially as shown and described, for the purposes 75 specified.

JACOB A. JACKSON.
